PHONOGRAPH

Emile C. Guedon, Audubon, N. J., assignor to
 Radio Corporation of America, a corporation of
 Delaware

Application July 29, 1939, Serial No. 287,292

1 Claim. (Cl. 74—191)

This invention relates to phonographs, and more particularly to the driving mechanism for the turntable thereof.

It is well known that difficulty is often experienced in operating electrically driven phonograph turntables at the desired speed. This may be due to a number of causes, such as variations in line voltage, variable loads, etc.

The primary object of my present invention is to provide a phonograph turntable drive which can be readily adjusted to provide the desired speed.

More particularly, it is an object of my present invention to provide an improved drive for phonograph turntables which can be readily adjusted to provide correct playing speed for the turntable.

Another object of my present invention is to provide an inexpensive, self-starting, motor-driven turntable for the playing of phonograph records.

In accordance with my present invention, I provide a self-starting, electric motor which is pivotally supported on a suitable frame or cradle and which has an approximately vertical drive shaft provided with a conical driving surface. In one form of my invention, I connect a friction wheel to the turntable for rotation therewith and arrange the motor in a manner such that the conical driving surface thereof is in constant engagement with the periphery of the friction wheel, the friction between the conical driving surface and the friction wheel effecting rotation of the turntable. I also provide adjusting means for the frame or cradle of the motor so that the motor can be readily adjusted to bring different portions of its conical driving surface into engagement with the periphery of the friction wheel. In this manner, the speed of the turntable can be readily altered to suit variable loads and variable voltage conditions.

In accordance with another form of my invention, I provide a pulley on the turntable shaft and couple the pulley to a friction wheel by means of a belt. The motor, as before, is pivotally mounted and has its conical driving surface in constant engagement with the friction wheel which, in this modification, is made adjustable along the conical driving surface to effect variations in speed.

The novel features that I consider characteristic of my invention are set forth with particularity in the appended claim. The invention itself, however, both as to its organization and method of operation, together with additional

objects and advantages thereof, will best be understood from the following description of two embodiments thereof, when read in connection with the accompanying drawings, in which

5 Figure 1 is a plan view of a turntable driving mechanism embodying one form of my invention.

Figure 2 is a sectional view thereof taken along the line II—II of Figure 1.

Figure 3 is a plan view of a phonograph drive mechanism showing another form of my invention, and

Figure 4 is a side elevation of the latter form of my invention.

Referring more particularly to the drawings, 15 wherein similar reference numerals designate corresponding parts throughout, I have shown, in Figures 1 and 2, a motorboard 1 which supports a frame 3 in which is rotatably mounted a spindle 5. Fixed to the spindle 5 is a rubber-tired disk 7 constituting a friction wheel, the disk 7 being connected to a turntable 9 by means of a plurality of upstanding pins 11 which are received in rubber grommets 13 secured to the turntable 9. This construction may be of the type disclosed, for example, in the U. S. patent to Blessing and Guedon, No. 2,157,158, and serves effectively to prevent the transmission of vibrations to a record supported on the turntable 9 during playing.

20 30 Fixed to the frame 3 are a pair of oppositely disposed brackets 15 formed with knife edges or other suitable fulcrums 17 on which a motor frame or cradle 19 is pivotally mounted. A suitable electric motor 21, preferably of the self-starting type, and having a driving shaft 23 provided with a conical driving surface or tip 23a, is pivotally carried by the cradle or frame 19 on a pair of oppositely disposed pins 25, the shaft 23 being disposed between the fulcrums 17 and the pivot pins 25. The center of gravity of the motor 21 is located to the left of the pivotal mountings 17 and 25 (as viewed in Fig. 2) so that the motor 21 always tends to rotate in a counter-clockwise direction and therefore the 25 conical driving surface 23a will always be maintained in engagement with the periphery of the friction wheel 7.

When energy is supplied to the electric motor 21, it is obvious that the friction between the conical driving surface 23a and the periphery of the rubber-tired friction wheel 7 will effect rotation of the wheel 7 and the turntable 9. To alter the speed of the turntable, an adjusting screw 7 is threaded into the frame 3 and is brought down into engagement with the cross-arm 19a of the

cradle 19. As the screw 27 is advanced in a downward direction, it will effect clockwise rotation of the cradle 19 and the motor 21 about the fulcrums or knife edges 17. This raises the conical driving surface 23a and at the same time tends to move it away from the periphery of the friction wheel 7. However, inasmuch as the center of gravity of the motor 21 is to the left of the pivot pins 25, it is obvious that the counterclockwise movement of the motor about the pins 25 will offset the corresponding clockwise movement of the motor assembly about the fulcrums 17, and the conical driving surface 23a will still be maintained in engagement with the periphery of the friction wheel 7, although at a larger diameter. This, of course, will increase the speed of the turntable. Conversely, if the adjusting screw 27 is retracted in an upward direction, the cross-arm 19 will follow it, and the motor assembly will pivot around the fulcrums 17 in a counter-clockwise direction to bring a portion of the driving cone 23a having a smaller diameter into contact with the friction wheel 7 and thereby reduce the speed of the turntable.

In the modification of my invention shown in Figures 3 and 4, the turntable spindle 5 has fixed thereto a pulley 31 which is connected by means of a belt 33 to a second pulley 35 rotatably mounted on the bottom extension of the adjusting screw 27 and fixed to a rubber-tired friction wheel 37. An idler pulley 39 carried on a pivotally mounted bracket 41 constantly maintains tension in the belt 33 under the influence of a spring 43.

Pivotal mounted on a bracket 45 is the motor 21 which is constantly biased in a clockwise direction by a spring 47 to maintain the conical driving surface 23a in constant engagement with

the friction wheel 37. By merely manipulating the adjusting screw 27 one way or the other, it is obvious that the friction wheel 37 will be moved along the conical driving surface 23a to thereby vary the speed imparted to the friction wheel 37 by the motor and thus to correspondingly vary the speed of the pulley 31 and the turntable mounting.

Although I have shown and described but two embodiments of my invention, I am fully aware that many other modifications thereof are possible. I therefore do not wish to limit myself except insofar as is made necessary by the prior art and the spirit of the appended claim.

I claim as my invention:

In a phonograph, the combination of a turntable, a friction wheel connected to and rotatable with said turntable, a motor frame, means pivotally mounting said motor frame for pivotal movement relative to said friction wheel, a motor pivotally carried by said frame and having a driving shaft provided with a conical driving surface, said motor shaft being disposed between the pivotal mounting of said frame and the pivotal mounting of said motor on said frame and the center of gravity of said motor being located on the same side of both of said pivotal mountings whereby said motor constantly tends to swing about both said mountings in a direction to effect engagement between said conical driving surface and said friction wheel, and adjustable means associated with said frame for adjusting said frame about said first named means whereby to vary the point of engagement of said conical surface with said friction wheel to thereby alter the speed imparted to said turntable by said motor.

EMILE C. GUEDON.
